UNITED STATES PATENT OFFICE.

HENRY KOCOUREK, OF JERSEY CITY, NEW JERSEY, ASSIGNOR TO JULIA E. STEWART,
EXECUTRIX OF JOHN K. STEWART, DECEASED.

STRAP-BRAKE.

1,255,432.

Specification of Letters Patent.

Patented Feb. 5, 1918.

Application filed December 28, 1916. Serial No. 139,385.

To all whom it may concern:

Be it known that I, HENRY KOCOUREK, a citizen of the United States, residing at Jersey City, in the county of Hudson and State of New Jersey, have invented now and useful Improvements in Strap-Brakes, of which the following is a specification, reference being had to the accompanying drawings, forming a part thereof.

10. The purpose of this invention is to provide an improved strap brake of the general character which comprises a metal strap and a multiplicity of shoes encompassed by the strap and adapted to engage a channel in the wheel to be held by the brake. It consists in the elements and features of construction shown and described, as indicated in the claims.

20. In the drawings:—Figure 1 is a side elevation of a portion of a brake embodying this invention, showing several of the shoes thereon.

Fig. 2 is a section at the line 2—2, on Fig. 1.

25. Fig. 3 is a mid-longitudinal section of a segment of the brake,—that is to say, a section in a plane transverse to the axis of the wheel to be held.

Fig. 4 is a perspective view of the brake shoe dissected,—that is, with its two members separated from each other.

Fig. 5 is a plan view of a sheet metal blank from which the friction member of the brake-shoe is formed by folding.

35. In the drawings 1 represents the metal strap of a brake of the type indicated, adapted to be clamped onto the wheel to be held by any suitable means which are represented in the drawings by the crank shaft, 2,

40. and link, 3, for drawing upon the unsecured end of the brake, the secured end being shown at 4. This invention relates to the construction of the brake shoes, each of

45. which comprises a channel-shaped friction member, 5, of stamped metal, preferably as usual, V-shaped in cross-section, which is formed from a blank shown in Fig. 5, having

50. at the opposite end portions lugs, 5^a, which are folded inward from the opposite sides, meeting at their edges and forming

55. a cover for the end portions of the channel, their outer surfaces being the seat for the strap, an aperture, 5^b, being thus left between these end portions through which

55. there is admitted a reinforcing member, 6,

which comprises lugs, 6^a, V-shaped to fit the channel, and connected by a shank, 6^b. The lugs, 5^a, folded inward as stated to form the cover of the channel, are extended on the side members of the channel, forming end-projecting lugs specially designated 5^c and 5^d respectively, these two lugs at the opposite ends of the channel members being distinguished by the circumstance that the lug, 5^c is depressed to form a recess in which the lug, 5^d, of the next adjacent shoe of the series is lapped upon the lug, 5^c, so that notwithstanding the successive lap of each shoe upon the next one in the series, the outer surfaces of the covers of the channels which form the surfaces for the seating of the strap are flush with each other so that the shoes are all pressed alike and radially of the wheel into the brake channel thereof. These lugs, 5^a, are folded inward as shown 75 so that the intermediate portions of the sides of the channel members project outward beyond the outer surfaces of said infolded lugs, as seen at 5^e, for engaging laterally with the edges of the strap to retain it 80 on the shoes. The reinforcing members, 6, preferably have their lugs, 6^a, which as stated are shaped to fit the channel of the member, 5, folded at an obtuse angle to the shank, 6^b, so that the said lugs stand at an 85 inclined position in the channel; and the outer ends of the lugs, 6^a, while approximately flush with the outer surfaces of the lugs, 5^a, on which the strap seats are very 90 slightly protuberant therebeyond, so that the pressure of the strap is first received, or exceptionally, received, by these edges of the lugs of the reinforcing member with the effect of forcing the reinforcing member 95 down into the channel of the friction member which is possible by reason of the inclined position of the lugs, 6^a, in the channel, said lugs being forced very slightly outward or apart from each other by the inward 100 pressure of the strap and thus engaged very securely with the inclined surfaces of the channel.

I claim:—

1. A strap brake comprising a metal strap for encompassing the wheel to be held by the brake, and a circumferential series of unattached shoes encompassed by the strap, each shoe having at one end a recess and at the other end a lug lodged in the recess of the next shoe.

2. A strap brake comprising a metal strap for encompassing the wheel to be held by the brake, and a circumferential series of unattached shoes encompassed by the strap, each shoe comprising a stamped metal channel-shaped member, having folded inward from the channel side and projecting end-wise of the channel at the opposite ends thereof lugs which are lapped respectively on and under the lugs of the next shoes in the series. 45
3. A strap brake comprising a metal strap for encompassing the wheel to be held by the brake, and a circumferential series of unattached shoes encompassed by the strap, each shoe comprising a channel-shaped member and a reinforcing member having end lugs shaped to fit the channel of the first member and an intermediate shank 50 connecting the lugs, the channel member having outwardly facing surfaces for lodgment on the strap, the lugs of the reinforcing member being flush with said surfaces when said reinforcing member is in position in the channel, whereby both said members of the shoe are exposed to the pressure of the strap. 55
4. A strap brake comprising a metal strap for encompassing the wheel to be held by the brake, and a circumferential series of unattached shoes encompassed by the strap, said shoes each comprising a channel-shaped member and a reinforcing member having lugs shaped to fit the channel of the first member, and an intermediate shank connecting the lugs, the channel member having its opposite sides extended at the end portions and folded inward over the channel to cover the end portions of the channel, 60 leaving an intermediate opening to receive the reinforcing member, said reinforcing member when inserted in the channel having its lugs at their outer ends protuding between and adjacent to the in-folded lugs of the channel member, whereby said reinforcing member is longitudinally stopped by the channel member and is exposed to the pressure of the strap forcing it into the channel. 65
5. A strap brake comprising a metal strap for encompassing the wheel to be held by the brake, and a circumferential series of unattached shoes encompassed by the strap, each shoe comprising a stamped metal channel-shaped member having folded inward from the channel sides and projecting end-wise of said member at the opposite ends lugs which are lapped respectively on and under the lugs of the next shoes of the series, the lug at one end of each shoe being 70 depressed to accommodate the lapping lug of the next shoe, the outer surfaces of said lugs constituting the seat of said channel members on the strap, the intermediate portions of the sides of the channels projecting beyond said strap-seating surface for engaging the straps laterally between them. 75
6. A strap brake comprising a metal strap for encompassing the wheel to be held by the brake, and a circumferential series of unattached shoes encompassed by the strap, each shoe comprising a channel-shaped member and a reinforcing member comprising end lugs inclined away from each other and a shank connecting them at an obtuse 80 angle to said lugs, the channel member having its channel partially covered for affording a seating surface for the strap, and an aperture in said seating surface to admit the reinforcing member there-through into the channel, the outer edges of said lugs of the reinforcing member when said member is seated in the channel being slightly protuberant beyond said outer strap-seating surface of the channel member. 85

In testimony whereof, I have hereunto set my hand, this 24 day of November, 1916.
HENRY KOCOUREK.
